VERTICALLY SWINGING FLEXIBLE DOORS

William Thomas Bateman, Alexandria, Va.

Application May 25, 1954, Serial No. 432,217

15 Claims. (Cl. 160—354)

This invention relates to swinging doors of heavy flexible sheet material and more particularly to swinging doors for cooler or storage rooms which are designed to be opened by the striking of freight carriers thereagainst.

It is the object of the present invention to provide flexible swinging doors for cooler or storage rooms which are of rugged construction, of few mechanical parts and which are characterized by low installation and maintenance costs.

Another object of the invention is to provide gravity hinge mountings for swinging doors in which the gravity hinges are disposed at the upper ends of the door only, for cooperation with rigid supporting arms for the flexible closures so that the opening movements of the doors can be initiated from oblique angles as well as directly from the front of the door opening, thereby eliminating the need for long approach aisles leading to the doorway. The high location of the hinge mounting excludes possibility of injury to the hinge mechanism, cargo loads or personnel in the operation of the doors.

The invention proceeds upon the principle of providing a closure of heavy flexible sheet material for a door opening which normally is adapted to be disposed in closed position by the provision of gravity hinges mounted on the upper parts of the door jambs of the door frame, which cooperate with pintle rods affixed to rigid arm assemblies from which are suspended the flexible panels or closures. The doors are opened with minimum abrupt shocks by the movement of merchandise carriers or pallets which strike against the flexible closures, which in turn transmit the force to the supporting arms for the flexible closures to open the doors on the axes of the gravity hinges and which operate automatically to return the supporting arms and flexible closures to their closed position following the clearance of the moving force through the doorway.

The simplicity of the gravity hinge embodied in the instant invention, composed of a pair of aligned bearing bushes for the vertical pintle and the arcuate track for the lateral terminal of the pintle rod, results in an easy movement of the parts with little friction, which is minimized to the extreme by the provision of a roller on ball bearings for the pintle rod extremity on the arcuate trackway.

Other objects and purposes will appear from the detailed description of the invention following hereinafter, taken in conjunction with the accompanying drawings, wherein—

Fig. 1 is a front elevation of a door opening provided with a pair of swinging doors of flexible sheet material in accordance with the invention;

Fig. 2 is an enlarged front elevation of the door assembly at the upper left portion of Fig. 1;

Fig. 3 is a sectional view along line 3—3 of Fig. 2;

Fig. 4 is a vertical sectional view along line 4—4 of Fig. 2;

2

Fig. 5 is a front elevation of the gravity hinge mounting with the parts shown in the open position of the door;

Fig. 6 is a horizontal sectional view along line 6—6 of Fig. 2;

Fig. 7 is a vertical sectional view along line 7—7 of Fig. 1;

Fig. 8 is a horizontal sectional view along line 8—8 of Fig. 1;

Fig. 9 is a vertical sectional view of a different embodiment of the invention showing an alternative arrangement for suspending the flexible door closure from its supporting arm as a variation from that shown in Fig. 4; and

Fig. 10 is a front elevation of the double-faced frame employed in the mounting shown in Fig. 9.

In the drawing is shown a door closure for a framed door opening 2 leading to a cooler room or a stock room of more general utility. The door opening 2 is framed by vertical jambs 3 and 3' on the opposite sides thereof and horizontal lintel 4 at the top thereof. In the illustrated embodiment of the invention, a pair of swinging doors 1 and 1' are shown mounted for pivotal movement about vertical axes adjacent each of the door jambs 3 and 3', but the invention may be realized as well for single swinging doors. Furthermore, since the construction of the doors 1 and 1' and the mountings therefor are identical, only one will be described in detail, the other being a counterpart, and in fact the doors, because of their symmetrical construction, are interchangeable.

The doors 1 and 1', which may be designated as curtain doors or flapper doors, are formed from heavy flexible sheet material of plastic or composite sheeting and are suspended from rigid supporting arms 20 and 20', respectively. I have found sheet material composed of 5-ply rubber and fabric sheeting highly practical. This sheeting is approximately $\frac{1}{6}$ " in thickness and is composed of three layers of rubber alternating with two layers of fabric, with the rubber layers outermost. This material may range in weight from $\frac{3}{4}$ to 1 pound per square foot, so that the weight of the flexible sheet material for a door opening of 7' x 7' may amount to forty to fifty pounds. The material resembles laminated fabrics used for belting, and heavyweight material is required, for not only must the material be capable of taking the repeated blows and impacts of modern mechanical battery and gasoline powered freight cargo carriers as the same strike against it, but these striking forces must also be transmitted through this material to effect an opening of the doors when these movable vehicles impinge thereagainst.

Small window panes 5 and 5', of plastic material, may be provided in each of the flexible panels 1 and 1' as a safety measure.

While gravity hinges have been known for a long period of time, the hinge assembly in accordance with the invention is particularly rugged and reliable. This arises from the fact that the bearing unit for the pintle rod which is affixed to the door supporting arm, may be formed integrally and may consist of a base strap 10 which may be affixed to the upper end of vertical jamb

3 or 3' of the doorway by means of screw bolts 14. If the jambs 3 and 3' are of metal, the base strap 10 may be welded thereto at the upper portion of the jamb. A lateral projection 11 extends from the lower end of the base strap 10 and a lateral projection 12 extends from the base strap 10 adjacent to the upper end thereof. The free end of projection 12 supports the lowermost portion of the semicircular track 13, the diametral ends of which curve upwardly from this point and merge with the enlarged upper end 10' of the base strap 10 (Fig. 5). A notch of V-shape or circular configuration is disposed at the lowermost point of track 13 to provide a secure

seat for the pintle roller, described hereinafter, in the closed position of the door. Projection 11 is provided with a circular opening 15 and projection 12 is provided with an aligned circular opening 16 which constitute bearing bushes for the pintle rod 21 of the hinge assembly as the same executes its rotary and reciprocating movements.

The spacing between the projections 11 and 12, which may amount to 2 feet, provides an effective guide for the up and down movements of the pintle rod 21 which may move $1\frac{1}{8}$ " as the same is rotated from its lowermost dwell to its highest positions at the extreme opening or closing limits of the door. Furthermore, the support of the free portion of the semicircular trackway by the projection 12 results in a stable mounting for the trackway at its mid-point to supplement the support thereof at the opposite ends thereof on enlarged base portion 10' (Figs. 2 and 5). Therefore, the gravity hinge unit, which may be formed integrally as one piece, lends itself to economical fabrication and easy mounting upon the door jamb.

The pintle rod 21, which is designed to form a component part of the gravity hinge, is preferably formed of $\frac{3}{4}$ " rod material of a length approximating $2\frac{1}{2}$ feet which, as described above, is rotatably and reciprocably movable in the bearing bush openings 15 and 16 of $2\frac{5}{32}$ " diameter. The upper end of the pintle rod is provided with lateral extension or offset 22 which overlies the central part of the inner portion of the arm 20. This extension is fitted at its free end with a roller 23 fastened thereon by bolt 24. The roller 23, which may be offset 3" from the rotary axis of the pintle rod, is mounted on ball-bearings so that it may roll easily on the track 13 as the door is swung from its closed and open positions. In fact, the door is supported by roller 23 resting on its arcuate track 13 and its smooth operation is facilitated by the guiding effects afforded by the movement of the pintle rod 21 in the bearing bushes 15 and 16. If the roller 23 is fitted with ball-bearings which require no oiling, it is then only necessary to oil periodically the bearing bushes 15 and 16 to assure a free and easy rotary movement of the doors.

The pintle rod 21 is drilled at displaced points therealong for the affixation thereof to the arm 20 supporting the flexible panel 1. As shown in Fig. 6, screw bolts 26 are passed through the diametral openings in the pintle rod 21 and are fastened to the inner end 25 of the arm 20 by means of threaded bolts 27. The openings in the pintle rod and the bolts 26 passing therethrough are disposed in the plane of offset arm 22 and in the plane of the supporting arm 20 so that when the arm 22 and the roller 23 supported thereby are in line with the lowermost part of the track 13, the door is in its closed position and is disposed within the plane of the door frame opening.

The supporting arm 20, as well as its companion supporting arm 20', is preferably framed of sheet metal and is composed of a front wall 28 and a rear wall 26 capped with a channel member 33. The front wall 28 is bent inwardly at its lower end at 29 and the rear wall 26 is bent inwardly at 27 to define a slotted opening 31 along the lower boundary of the supporting arm which, in the illustrated embodiment of the invention, is formed of a configuration resembling generally a pair of juxtaposed trapezoids. The inner end of the arm adjacent to the hinge mounting is enlarged to provide a secure mounting for the pintle rod 21, while the free end 30 of the arm 20 need be of only small depth and a fraction of the depth of the other end, since it serves merely as a closure for the framework of the mounting arm and possibly as an end support for the slotted cylindrical tube 32 acting as a guide passage which extends horizontally from the small end 30 across the full length of the mounting arm 20. The slotted cylindrical tube 32 is also supported by openings in transversely disposed reinforcing

plates 33' and 34 at spaced points along the length of the supporting arm.

In the preferred embodiment of the invention, as shown in Fig. 4, the door flap 1 of sheet material is looped at its upper end in the form of a cylindrical loop 9 formed by rows of stitching 8. The looped end is slid into the cylindrical tube 32, which may have an internal diameter of $\frac{3}{4}$ ". Following the disposition of the looped end 9 of the curtain door within the cylindrical tube 32, with the free end of the door projecting through the slotted passage 31, the rod 36 is slid into the interior of the loop 9 to provide a secure support for the upper end of the curtain door. This support is secured firmly by the application of the end closure 30 to the free end of the arm. The steel rod 36 may approximate a diameter of $\frac{1}{2}$ " in order to fill in completely the space within the slotted cylindrical tube 32.

In order to improve the operating action of the curtain door, the slotted opening 31 along the lower boundary of the supporting arm 20 is lined with rounded surfaces 35 and 35' which may be in the form of $\frac{1}{2}$ " diameter rods welded to the extremities of the horizontal frame projections 29 and 27, respectively. These rods permit a limited flexing of the curtain door 1 as the latter is subjected to impacts of vehicles preparatory to the transmission of these impacts to the supporting arm 20. This improves the operating cycle of the opening and closing movements of the door and also prevents any undue wear of the flexible panel at its point of connection with the supporting arm therefor.

In the embodiment of the invention illustrated in Figs. 9 and 10, the supporting arm 20 is similar in construction to that described above. However, the mounting support for the flexible closure is modified by the provision of a double-faced sheet metal support for the flexible fabric which extends beyond the slotted passage 31 bounded by the tubular rods 35 and 35'. The sheet metal support is formed of opposed plates 40 and 42 corresponding generally to the contour of the supporting arm 20, but extending therebeyond for approximately a 2" margin. The upper edge or junction of the plates 40 and 42 is rounded into a generally cylindrical formation 41 and is disposed horizontally in order to fit within the slotted tube 32 mounted across the length of the supporting arm 20. The projecting boundaries of the plates 40 and 42 are drilled with staggered rivet holes which are aligned in the plates 40 and 42. The heavy flexible plastic or rubber sheeting is inserted between the plates 40 and 42 by springing them apart and thereafter the same may be united by riveting the three plies together with rivets 45.

As shown in Fig. 9, the impacts on the flexible door 43 are transmitted therefrom to the sheet metal assembly 40 and 42 and therefrom to the supporting arm 20, with wear or fatigue on the parts being minimized by the rounded surfaces afforded by cylindrical rods 35 and 35'.

When the closures described above are used as swinging doors for cooler rooms, it is desired to seal the doors as much as possible against the loss of cooling air from the enclosure. For this purpose a flexible sealing flap 7 is supported from the horizontal lintel 4 and extends in close proximity to the upper edge of the supporting arms 20 and 20'. The sealing flap 7 does not extend to the gravity hinge assembly in order not to interfere with the operation thereof. This flap does not interfere with the rise of the doors since the arms 20 clear this flap as soon as they start turning. Likewise, the vertical jambs 3 may be lined as far as the hinge units with sheet metal sealing straps 43. These straps may be affixed to the jambs by any suitable fasteners 49, as shown in Fig. 8.

As stated above, the door closures and operating mechanisms may be applied easily to existing door openings by first mounting the base strap 10 onto the jamb with the pintle rod in the assembly. Thereafter, the roller

23 may be affixed to the lateral extension arm 22 of the pintle rod and the large end of the supporting arm 20 may be bolted to the pintle rod by means of bolts 26 and nuts 27. The removable cap 30 on the small end of the supporting arms 20 is then removed to permit the sliding of the upper end of the flexible door panel into the supporting arm whether it be of the construction shown in Fig. 4 or that shown in Fig. 9, whereupon cap 30 is replaced. The flexible sealing straps 7 and metallic sealing straps 48 may be applied to the lintel and jambs to prevent undue leakage of air from the chamber or storage room to which the doors are applied.

Upon wearing of any of the parts, replacements may be made by the simple dis-assembly and assembly of the parts as described hereinabove.

The supporting arm for each door flap may be fabricated from any desired sheet metal, for example, 14 gauge sheet steel. The parts may be integrated by welding, bolting, or similar fastening expedients. The small end of the arm 20 remote from the pintle rod 21 may be cut to adapt the door to varying sizes and the end closure 30 therefor may be varied accordingly or may even be omitted. The supporting arm may weigh as much or more than the flexible panel supported thereby. The combined weight is correlated to the degree of incline of the trackway 13 to permit the opening of the door to be executed without need for the imposition of undue force thereagainst. For example, the lesser the degree of incline of the trackway, the smaller is the force required to raise the door as it turns.

I claim:

1. A swinging door of heavy flexible sheet material within a door frame, comprising a panel of said sheet material, a rigid supporting arm engaging only the upper portion of said panel, a vertical hinge of limited length affixed to one end of said arm, and means for mounting said hinge in only the upper part of said door frame for rotary movement about a vertical axis, leaving free the edge of said panel below said hinge, constituting the major height of said panel, and the opposite edge of said panel substantially in its entirety.

2. A swinging door of heavy flexible sheet material mounted for rotary movement on a door jamb, comprising a panel of said sheet material, a rigid arm for freely supporting said panel from only the upper portion thereof, a vertical hinge element of limited length affixed to one end of said arm and provided with a lateral extension at the upper end thereof, and a cam track mounted on the upper portion of the door jamb cooperating with said hinge element and lateral extension to automatically return said door to closed position following the flapping of the door to open position.

3. A swinging door of heavy flexible sheet material adapted for rotary movement on a door jamb about a vertical axis, comprising a panel of said sheet material, a rigid supporting arm for detachably connecting only the upper part of said panel to said arm, said arm having a vertical hinge element of limited length affixed to the end thereof, a slotted guide passage extending through said arm from the opposite end thereof and communicating with a slot extending across the bottom of said arm, and interengaging means between said guide passage and the upper part of said panel for suspending said panel through said slot, leaving free the vertical edge of said panel below said vertical hinge element.

4. A swinging door of heavy flexible sheet material adapted for rotary movement on a door jamb about a vertical axis, comprising a panel of said sheet material, a rigid hollow supporting arm for detachably connecting only the upper part of said panel to said arm, said arm having a vertical hinge element of limited length affixed to the end thereof, a slotted cylindrical guide passage extending horizontally through said arm from the opposite end thereof and communicating with a slot extending across the bottom of said arm, a closure for the last-

mentioned end of said hollow supporting arm, and interengaging means between said guide passage and the upper part of said panel for suspending said panel through said slot, leaving free the vertical edge of said panel below said vertical hinge element.

5. A swinging door as set forth in claim 4 wherein the height of the arm at the end of the closure is a fraction of the height of the arm at the end affixed to the vertical hinge element.

10 6. A swinging door as set forth in claim 4 wherein said hollow supporting arm is provided with at least one transverse reinforcing plate between the opposite ends thereof to reinforce the arm and to provide intermediate support for said cylindrical guide passage.

15 7. A swinging door as set forth in claim 4 wherein said vertical hinge element is provided with a lateral extension at the upper end thereof in the plane of said arm, and a freely rotating rolling member adjacent the end of said extension.

20 8. A swinging door of heavy flexible sheet material adapted for rotary movement on a door jamb about a vertical axis, comprising a panel of said sheet material having a cylindrical loop at the upper edge thereof, a rigid supporting arm for detachably connecting the

25 cylindrical loop of said panel to said arm, said arm having a vertical hinge element of limited length affixed to the end thereof, a slotted cylindrical tube extending horizontally through said arm from the opposite end thereof and communicating with a slot extending across the

30 bottom of said arm, said slotted tube receiving the cylindrical loop of the panel with the rest of the panel passing through said slot, a cylindrical bar extending into the interior of the loop, and a closure for the last-mentioned end of said supporting arm and the ends adjacent thereto of the slotted tube, loop and bar, leaving free the vertical edges of said panel below said closure and said vertical hinge element.

35 9. A swinging door as set forth in claim 8 wherein the slot extending across the bottom of the arm is bordered by rounded surfaces to minimize wear on the flexible panel adjacent to the junction lines between the panel and the arm.

40 10. A swinging door of heavy flexible sheet material adapted for rotary movement on a door jamb, comprising

45 a panel of said sheet material, a rigid supporting arm for detachably connecting the upper part of said panel to said arm, said arm having a vertical hinge element of limited length affixed to the end thereof, a slotted cylindrical tube extending horizontally through said arm from

50 the opposite end thereof and communicating with a slot extending across the bottom of said arm, a double-faced sheet-metal frame extending from a rounded junction therebetween having the junction fitting within the slotted tube and the frame extending through said slot beyond the bottom boundaries of said arm, and means for affixing the upper edge of said panel of sheet material between the opposite faces of said frame leaving free the opposite vertical edges of said panel.

55 11. A swinging door as set forth in claim 10 including a closure for the last-mentioned end of the supporting arm and the ends adjacent thereto of the slotted tube and double-faced frame, and rounded surfaces adjacent to the slot extending across the bottom of the supporting arm to minimize wear on the double-faced frame adjacent to the junction lines between said frame and arm.

60 12. A swinging door of heavy flexible sheet material within a door frame, comprising a panel of said sheet material, a rigid supporting arm engaging only the upper portion of said panel, a vertical pintle rod of limited length affixed to one end of said arm and extending above

65 the upper edge of said arm, a lateral extension projecting from the upper end of said pintle rod superposing and in the plane of said arm, a roller member on the free end of said extension, a gravity hinge affixed to the door frame adjacent to said pintle rod comprising a sheet

metal base affixed to the vertical edge of the door frame, a semi-circular track at the upper end of said base for supporting said roller member, lateral projections at the top and bottom of said base provided with aligned apertures for guiding the pintle rod in vertically reciprocating movements, said track being inclined upwardly from its radial median in both directions to permit the panel and supporting arm therefor to swing in either direction from the plane of the door frame and to be returned automatically thereto as the roller drops to its lowest median point by gravitational force.

13. A swinging door as set forth in claim 12 wherein the sheet metal base of the gravity hinge affixed to the door frame is enlarged at its upper end to integrate the opposite terminals of the semi-circular track, and in addition the lateral projections extending from said base are also integral therewith.

14. A swinging door as set forth in claim 13 wherein the upper lateral projection extending integrally from the sheet metal base also supports the lowest median point of the circular track.

5

10

15

20

15. A swinging door as set forth in claim 12 wherein the lowest median point of the circular track is recessed to provide a secure seat for the roller member therein.
